UNITED STATES PATENT OFFICE.

WILLIAM H. McCLELLAND, OF HUNTINGDON, PENNSYLVANIA, ASSIGNOR, BY MESNE ASSIGNMENTS, TO ROY P. M. DAVIS, OF MOUNT UNION, PENNSYLVANIA.

BRICKMAKING MACHINE.

Application filed December 15, 1924. Serial No. 755,944.

To all whom it may concern:

Be it known that WILLIAM H. McCLELLAND, a citizen of the United States of America, residing at Huntingdon, in the 5 county of Huntingdon and State of Pennsylvania, has invented certain new and useful Improvements in Brickmaking Machines, of which the following is a specification.

My invention relates to brick making machines and more particularly to machines 10 for making silica brick.

The object of my invention is to provide efficient means for automatically moving the mold supports with molds thereon to filling 15 and dumping positions respectively.

Other and further objects of the invention will be in part obvious and in part described as the specification is proceeded with.

In the accompanying drawings forming 20 part of this specification:

Figure 1 is a side elevation of a portion of a brick making machine showing the invention;

Figure 2 is a plan view of the carriage, one 25 side being broken away;

Figure 3 is an end elevation of the invention;

Figure 4 is a detail side elevation of the mold block;

Figure 5 is a detail side elevation of the 30 carriage;

Figure 6 is a section on the line 6—6 of Figure 5;

Figure 7 is a detail section through the 35 mold block;

Figure 8 is a detail view of the carriage operating cam;

Figure 9 is an end elevation partly in section of the carriage operating cam;

Figures 10 and 11 are detail views of the 40 mold plate supporting and actuating arms;

Figure 12 is a detail view of the mold lift shaft bearing;

Figure 13 is a side elevation partly in 45 section of the carriage guide wheel;

Figure 14 is a detail end view of the bottom carriage track;

Figure 15 is a bottom plan view of the upper track; and

Figure 16 is a section on the line 16—16 in Figure 15.

Referring more particularly to the drawings wherein like reference numerals denote

corresponding parts throughout the several views, 1 represents the reciprocating carriage 55 of the brick making machine upon which the mold supports, hereinafter described, are mounted. The carriage 1 comprises end uprights or beams 2, and horizontally disposed top and bottom connecting beams 3, 60 corner angle braces 31 being employed for an obvious purpose. Axles 4 extend between the bottommost connecting beams 3 at each end of the carriage and have mounted thereon the grooved wheels 5. These wheels rest 65 upon and are adapted to snugly engage the arrow shaped treads 73 of the tracks 6, when the carriage 1 is reciprocated, in a manner hereinafter described. The tracks 6 are formed with depending flanges 71 to facilitate anchoring the tracks in the floor or other suitable base 72.

The carriage 1 is guided at its upper end by rollers 15 which engage the T rail 16, supported in the main frame of the machine, 75 in any suitable manner not shown. The rail 16 comprises the channel 23, to which a pair of angle beams 24, are secured by any suitable means such as the bolts or rivets 25. These rollers 15 are mounted on shafts 17, 80 supported in adjustable bearings 18, in turn supported upon the U-shaped brackets 19, mounted on the upper end of each pair of uprights 2. Adjusting bolts 20 permit of the rollers being tightly forced against the 85 T rail 16. Upper and lower end plates 21 and 22 respectively, connect and brace the uprights 2, and the lower end plates also serve as a support for the mold supports hereinafter referred to.

Reciprocation of the carriage 1 is effected by means of a rocker element 7, comprising pairs of spaced and downwardly diverging channel beams 8, the upper ends of which have passing therethrough a shaft 9, upon which the rocker element as a unit rocks. The shaft 9, is mounted in suitable bearings 10 carried by the horizontally disposed beam 11, in turn supported by the main frame uprights 12. The lower end portions of the beams 8 are connected by a cross beam 13, the intermediate side portions of which have connected thereto downwardly extending channel beams 14 and converging beams 26, connected to a plate 27 as by bolts or the like 28. A connecting rod 29 pivotally con-

nected to the beam 14 and plate 27, as at 74, connects the rocker element 7 with the reciprocating carriage 1 by means of a post or upright 30 mounted on the carriage, and to 5 which post the rod 29 is pivoted, as at 75.

The rocker element 7 is actuated to and fro by means of a double faced cam 32, mounted upon a shaft 33, constantly driven by any suitable means (not shown). The 10 face 34 of the cam engages the roller 35 on one of the channel beams 8 to push the rocker element toward the right Figure 1, and the cam face 36 engages the roller 38 on the other beam 8 to move the rocker element in the opposite direction to that just described. This movement of the rocker element, causes a corresponding, reciprocatory movement of the carriage 1.

The double cam 32 is made up of the two 20 arms 39 and 40 keyed to the shaft 33. The arm 39 has a segmental plate 60 bolted thereto, which provides the cam face 36 previously referred to, and the arm 40 has a segmental plate 41, to the edge of which is 25 bolted a segmental strip 42, by means of bolts 43, which bolts 43 also pass through the plate 60. Washers 44 are employed to space apart the segmental plates 60 and 41 and the segmental strip 42 to provide the 30 broad cam face 34.

Secured at each side of the end plates 22 of the carriage 1 by means of bolts 44' are a pair of spaced transversely disposed angles 45. Extending between the end plates 22, 35 with their ends resting on the bottommost of the traverse angles 45, are two pair of longitudinally disposed channel members or beams 46 (one pair at each side of the end plates). These channel members are secured 40 to the end plates by angle brackets or braces 47, bolts 48 being employed for this purpose. Projecting upwardly from each end of the carriage and from each side of the angle beam and channel beam construction just 45 described, are two pair of mold shaft bearing brackets or arms 49-49' in which the mold lift shafts 50-50' are journaled. It will of course be understood that there are 50 two mold lift shafts at each side of the carriage. Bolts 51 passing through openings 70 in the bearings 49-49' serve to secure the brackets or bearings 49-49' to the channel beams 46.

Mounted upon and keyed to the shafts 55 50-50' are mold lift arms 58-58' (there being two arms for each mold lift shaft) to which are secured by means of bolts 53, the bottom mold plates or mold supporting plates 52-52' respectively. These arms 60 58-58' and mold plates 52-52' when in the position illustrated in Figure 2, rest upon and are supported by castings or mold blocks 51-51', formed with outwardly projecting integral arms 54-54' (there being 65 two arms for each mold block) through the

outer apertured ends of which the respective shafts 50-50' loosely extend for relative turning movement therein. The bottoms of the mold blocks rest upon and are supported by the cross supports 84 which in turn rest 70 upon and extend between the channel beams 46 of the carriage 1. The height of mold blocks can readily be adjusted by means of the adjusting bolts 76 which project upwardly from the mold block supports 84 75 and engage in the threaded openings 77 formed in the bottoms of the mold blocks. These beams 46 carry abutment members 56-56' which engage pedestals 57 for the purpose of supporting and bracing the carriage 1, during the mold filling operation, as will be more fully described hereinafter. 80

As previously described the carriage 1 is reciprocated by means of the oscillating rocker element 7, in turn actuated to and 85 fro by means of the double faced cam 32, which rotates about the axis of shaft 33. Assuming the carriage 1 to be in Figure 1 position or the position assumed when the carriage has been moved to the right along 90 tracks 6 to the limit of its movement in this direction, the mold block 51 (the block to the left in Figure 1) will be in filling position directly over the pedestal 57, and under the hopper (not shown). A mold 58^a is now 95 delivered from the sander (not shown) and placed on the mold plate 52, and the mud which is then released from the hopper drops down into the mold completing the filling operation. This operation takes place 100 simultaneously at both sides of the machine.

The movement of the carriage is now reversed by the action of the rocker element until figure 2 position is reached. It may 105 here be noted that weighted belts 61 are attached to the carriage, at each end thereof by means of angles 62, bolts 63 being employed for this purpose. These belts which operate over rollers 64, serve to keep the tracks 6 free of mud and grit. As the 110 weighted belts 61 are described and claimed in my co-pending application Serial No. 755,942, filed December 15, 1924, no further description thereof is deemed necessary. When Figure 2 position is reached the previously filled mold on mold plate 52 will 115 be in dumping position, and the mold 52' on the other or right end of the carriage will have been moved to filling position with the abutment member 56' resting upon the pedestal 57. The left hand mold dump shaft 50, is now rotated in a clockwise direction in a manner about to be described.

Driving shafts 64 and 64' are respectively 120 arranged adjacent opposite ends of the carriage in the path of movement of the shafts 50-50'. These shafts 64-64' are provided 125 with female coupling members 65-65' at their respective ends adapted to be engaged by the corresponding male members 66-66' 130

on the mold lift arm shafts 50—50'. The shafts 64—64' are oscillated at predetermined intervals through the medium of arms 67—67' and connecting rods 68—68'; the connecting rods being connected to suitable actuating means (not shown). Consequently as the carriage 1 reaches Figure 2 position, the squared male members 66 of the shaft 50 engages in the correspondingly shaped female members 65 of the shaft 64, and at the moment the shafts become connected for simultaneous movement, the connecting rod 68 is elevated, causing the shaft 64 to make a partial rotation in a clockwise direction. The mold plate 52 together with the filled mold thereon is thus swung upwardly and outwardly until the filled mold is delivered to a dump table (not shown) from which it is finally deposited upon the tracks 69 leading to the stripper (also not shown), where the bricks are removed from the mold, in the manner described in my copending application 755,939 filed December 15, 1924.

25 After the mold is removed the mold lift shaft 50' is caused to rotate in a reverse or anti-clockwise direction sufficiently to carry the mold plate 52 over the dead center line. The carriage is now caused to move to the right to Figure 1 position, by the rocker element 7, and as this movement takes place the male member 66 on shaft 50 becomes disengaged from the female member 65 on the shaft 64. As the mold plate 52 is only supported by arms 58 when the shafts 50 and 64 are coupled, it drops of its own weight upon the mold block 51. When the mold plate strikes the mold block any mud adhering thereto is jarred loose.

40 When the carriage reaches its limit of movement to the right or Figure 1 position, the mold on the mold plate 52' will have been previously filled and consequently will be ready for the dumping operation. This takes place when the squared male member 66' interlocks with or engages the correspondingly shaped female members 65' on the shaft 61', and the shaft 64' is rotated in a clockwise direction through the medium of the arm 67' and connecting rod 68' and any suitable actuating means (not shown) for lifting the connecting rod 68'. After the filled mold on plate 52' has been transferred to the dump table (not shown) the shaft 64' is slightly rotated in the opposite or counter clockwise direction sufficiently to return the mold plate to a position slightly beyond dead center and above the mold block 51'. The carriage is then moved toward the left and as this movement takes place, the shafts 50' become disconnected from the shaft 64', thus permitting the mold lift arms 58' and the mold plate 52' to drop of their own weight, until the plate 52' strikes the mold block 51'.

The cycle of operation just described is the same on both sides of the machine. Two molds, one on each side of the carriage are filled simultaneously and as a shaft 50 on one side of the machine is rotated to lift a filled mold, a corresponding shaft 50 on the opposite side of the machine is rotated by similar mechanism for the same purpose.

Having thus described my invention, what I claim as my invention is:

1. A brick making machine including a carriage, a mold supporting plate swingably mounted on said carriage, means for reciprocating said carriage to move said mold supporting plate to mold filling and dumping positions and operative means for swinging said mold plate with mold thereon about a common axis when the dumping position is reached.

2. A brick making machine including a carriage, a mold supporting plate carried by said carriage, means for reciprocating said carriage to move said mold plate to mold filling and dumping positions, and means for swinging said mold plate with mold thereon about a common axis, in a direction transverse to that of the carriage movement, operative when said dumping position is reached.

3. A brick making machine including a carriage, a mold supporting plate swingably supported by said carriage, a mold block upon which said plate normally rests, means for reciprocating the carriage to move the mold plate to mold filling and dumping positions, means for swinging said mold plate with mold thereon about a common axis away from said mold block to dump the mold, and then swing said mold plate in a return direction beyond dead center and releasing the same to drop by gravity upon said mold block.

4. A brick making machine including a carriage, a mold block, a mold supporting plate swingably mounted on said carriage and normally resting on said mold block, means for reciprocating said carriage to move said plate to mold filling and dumping positions, means operable when said dumping position is reached to swing said mold plate away from said mold block to dump the mold and to cause said plate to be returned to normal position and forcibly contact with said mold block.

5. A brick making machine including a carriage, a mold lift shaft journaled in said carriage, a mold block having arms loosely journaled on said shaft, mold lift arms keyed to said shaft, a mold plate secured to said arms and normally resting on said mold block, means for reciprocating the carriage to move the mold plate to filling and dumping positions, means for actuating the mold lift shaft, operable when said dumping position is reached, for swinging the

mold plate away from and back to contact with the mold block and means for adjusting the position of the mold block.

6. A brick making machine including a carriage, a mold lift shaft journaled in said carriage, a mold plate keyed to said shaft, means at opposite ends of the machine for engaging said shaft to cause said mold plate and mold thereon to be swung about the axis of said shaft to dump said mold, means for reciprocating said carriage to bring opposite ends of said shaft alternately into engagement with said shaft engaging means.

7. A brick making machine including a carriage, a mold lift shaft journaled in said carriage, a mold plate swingable with said

shaft, means for reciprocating said carriage normally idle, drive shafts at each end of the machine, coupling means on the ends of said mold lift shaft adapted to engage 20 with corresponding coupling means on said drive shafts when said carriage reaches its limit of movement in opposite directions, and means for rotating said drive shafts operable when said coupling means are operatively engaged.

In testimony whereof I affix my signature in presence of two witnesses.

WILLIAM H. McCLELLAND.
